UNITED STATES PATENT OFFICE.

WILLIAM A. FRERET, OF WASHINGTON, DISTRICT OF COLUMBIA, ASSIGNOR TO NATIONAL LIME ASSOCIATION, OF WASHINGTON, DISTRICT OF COLUMBIA, A CORPORATION OF THE DISTRICT OF COLUMBIA.

METHOD OF PREPARING BUILDING UNITS.

No Drawing.

Application filed August 22, 1923. Serial No. 658,841.

To all whom it may concern:

Be it known that I, WILLIAM A. FRERET, a citizen of the United States, and resident of Washington, in the District of Columbia, 5 have invented certain new and useful Improvements in Methods of Preparing Building Units, of which the following is a specification.

My present invention relates to building 10 units and to the process of producing the same.

My invention concerns particularly a method of preparation of such units where cement, lime, gypsum, or combinations of 15 any or all of the above, are used as the cementitious binders.

It has been found impossible in the past 20 to produce building units having perforations or apertures therein in which lime, cement, or gypsum are used as the cementitious or binding agent, by an extrusion process. It has long been the practice to form clay bricks by this process, in fact many particular advantages accrue as a result 25 from the use of such a process in the production of building units of clay.

It has also been known that mixtures containing lime, cement, or gypsum, when in a fluid, semi-fluid, or plastic mass, are brought 30 into contact with machines of the type used for extruding clay bricks commonly made of iron or alloys thereof, that the mass tends to stick and adhere to the parts of the machine to such an extent that the machine is clogged and the work cannot be continued 35 without thoroughly cleaning off the adhering particles. Such machines can only make comparatively few blocks and, therefore, the repeated cleaning made necessary makes the 40 process of extrusion, when used with these materials, impracticable.

The affinity of lime, cement or gypsum for iron and its alloys, is such that once the material begins to solidify on these metallic 45 parts, water will not wash it off, but it becomes necessary to chisel, scrape, or otherwise forcibly separate the two materials. The condition of the surface of the iron apparently has no effect upon the degree of 50 affinity of these materials therefor. For instance, a machine having a polished steel aperture would not extrude blocks in which lime was the binding agent for a time appreciably longer than the same machine pro-

vided with an aperture made of cast iron 55 having an unfinished surface.

I do not attempt to explain the nature of this affinity which makes itself so manifest under these conditions, and which has heretofore limited the production of blocks in 60 which cement, lime or gypsum were used as a cementitious agent, to an operation which includes pressing, tamping, pouring or forming within a mould-like structure.

I have discovered, however, that if the ordinary machine of the type commonly known in the trade as the auger or screw feed, of iron or its alloys, be coated or plated with, or have its parts usually coming in contact with the mass to be formed into 70 bricks replaced by, non-ferrous material of a metallic nature, extrusion may be commercially carried out.

Among the metallic substances that have been found to have no unusual affinity for 75 lime, cement or gypsum, are copper, tin, aluminum and nickel. Various alloys containing these elements have been also found to give very satisfactory results.

I do not prefer any particular form of 80 device for carrying out my invention, as any extrusion machine of a type adapted to produce building blocks may be used, provided its extrusion orifice and other parts coming in contact with the material being extruded 85 include any of the above non-ferrous metals in their composition to a substantial degree. It will be obvious that combinations of iron and the above, may be used where the non-ferrous metal is present in a sufficient quantity 90 to outweigh the undesirable characteristics of the ferrous material. However, I am not at present informed of the preferred composition or combination of ferrous and non-ferrous material which produces the 95 most efficient results. It will be readily seen that the presence of ferrous material to an appreciable extent will detract from the efficiency of the machine and the process, by introducing the undesirable quality of adhérence. 100

It may be found desirable in some cases, to apply heat to the extruded block before being used as a building element. Obviously such heat, where found desirable, may be 105 applied either in the machine as the block is being extruded, or afterwards. The former has the advantage of confining this

step to the operation of extrusion and does not require separate handling.

What I claim is:—

1. A process of producing building units which includes the step of extruding a plastic mass containing a compound of calcium through an orifice, the surface in contact with said mass comprising a non-ferrous metal.
- 10 2. A process of producing building units which includes the step of extruding a plastic mass containing a compound of calcium through an orifice, the surface in contact with said mass including copper.

3. A process of producing building units 15 which includes the step of extruding a plastic mass containing a compound of calcium through an orifice, the surface in contact with said mass including an alloy of copper.

4. A process of producing building units 20 which includes the step of extruding a plastic mass containing a compound of calcium through an orifice, the surface in contact with said mass including brass.

In testimony whereof, I affix my signature.

WILLIAM A. FRERET.
